UNITED STATES PATENT OFFICE.

CHARLES H. SHAW, OF BROOKLYN, NEW YORK, ASSIGNOR TO SEABURY & JOHNSON, OF NEW YORK.

SULPHUR CANDLE.

SPECIFICATION forming part of Letters Patent No. 390,314, dated October 2, 1888.

Application filed May 16, 1887. Serial No. 238,404. (No model.)

To all whom it may concern:

Be it known that I, CHARLES H. SHAW, of Brooklyn, in Kings county and State of New York, have invented a certain new and useful 5 Improvement in Disinfectants, of which the following is a specification.

The object of my improvement is to facilitate the burning of sulphur as a disinfectant.

I will describe in detail a disinfectant embodying my improvement, and then point out the novel features in claims.

In the accompanying drawings, Figure 1 is a perspective view of a candle embodying my improvement. Fig. 2 is a transverse vertical 15 section of the same.

Similar letters of reference designate corresponding parts in the above figures.

The candle in this example of my improvement has a body, *a*, of cylindric form, provided on the upper side, at about the center, with a nipple or projection, *a'*.

Around the body *a* extends a band, *b*, which is preferably made of metal and extends slightly above the top of said body in order that it 25 may prevent the flowing over of any liquefied sulphur upon any article on which the candle may be placed and burned. This band may simply be retained by friction in place around the body, or it may be secured in any other 30 suitable manner. There may be a plate of metal beneath the bottom of the body *a* of the candle, if desirable, and in case such a plate should be employed it might be secured to the lower edge of the band *b*.

35 The candle in this example of my improvement is shown as being of large diameter com-

pared with its length or height, and it is desirable to make it in this way in order that a large surface of the sulphur shall be exposed for combustion. I employ a wick or wicking 40 consisting of threads or fibers of combustible material distributed throughout the entire body *a* of the candle, or the entire upper portion of the body, as well as the nipple or projection *a'*. I have represented such thread or 45 fiber by short lines in Fig. 2, and marked such lines with the letter *c*.

Obviously a candle embodying my improvement may be made in other shapes—as, for instance, square or approximately square, or 50 of other polygonal contour.

A candle embodying my improvement will burn slowly and without entailing any serious danger of conflagration.

What I claim as my invention, and desire to 55 secure by Letters Patent, is—

1. A sulphur candle provided with a surrounding band of metal projecting slightly above the upper side or end of the main portion or body of said candle, substantially as 60 specified.

2. A sulphur candle consisting of sulphur formed into a block or mass and having wicking consisting of fibers or threads of combustible material distributed throughout the upper portion of the block or mass, substantially 65 as specified.

CHARLES H. SHAW.
